CLAIM

I claim the ornamental design for a textured stress ball, as shown and described.

DESCRIPTION

FIG. 1 is a perspective view of the textured stress ball;
 FIG. 2 is a front side view thereof;
 FIG. 3 is a rear side view thereof;
 FIG. 4 is a right side plan view thereof;
 FIG. 5 is a left side plan view thereof;
 FIG. 6 is a top side view thereof; and,
 FIG. 7 is a bottom side view thereof.

1 Claim, 7 Drawing Sheets
